UNITED STATES PATENT OFFICE.

ALEXANDER THOMSON, OF SOURLAKE, TEXAS.

WASH-PIPE VALVE.

Application filed August 8, 1922, Serial No. 579,432. Renewed February 23, 1924.

To all whom it may concern:

Be it known that I, ALEXANDER THOMSON, citizen of the United States, residing at Sourlake, in the county of Hardin and State 5 of Texas, have invented certain new and useful Improvements in Wash-Pipe Valves, of which the following is a specification.

This invention relates to new and useful 10 improvements in a wash pipe valve, and is particularly adapted to be used in connection with a wash pipe, in washing the strainer in a deep well.

One object of the invention is to provide a device of the character described adapted 15 to be attached to the upper end of a wash pipe for the purpose of ascertaining when the "set pipe" is released from the screen.

Another object of the invention is to provide a means for shutting off practically 20 all of the water forced down into the "set pipe" at the proper time to accurately determine whether or not the set pipe has been detached from the screen before withdrawing the set pipe from the bore of the 25 well.

With the above and other objects in view this invention has particular relation to certain novel features of construction, operation and arrangement of parts, an example 30 of which is given in this specification and illustrated in the accompanying drawings wherein:—

Figure 1 is a vertical sectional view showing my invention attached to the upper 35 end of a wash pipe.

Figure 2 is a vertical sectional view of the valve and ring; and,

Figure 3 is a transverse sectional view of the device taken on the line 3—3 of Figure 40 2, and shown surrounded by the valve seat.

Referring now more particularly to the drawings, wherein like numerals of reference designate similar parts in each of the figures, the numeral 4 represents the well 45 casing which remains permanently in the bore of the well. The numeral 5 designates what is commonly known as the set pipe, which is used in setting the well screen 6. Between two sections of the set pipe 5 there 50 is inserted the inwardly projecting ring 7, and securing these two sections of pipe together and holding this ring 7 in position is the coupling 8. The screen is connected onto the set pipe by means of the coupling 9.

Within the casing 4 and above the coupling 9 is what is commonly termed a lead

seal 10 which is intended to prevent any fluid from passing up from around the screen and out to the surface of the ground, except through the screen 6, and it is usual and customary to leave at least one joint of set pipe secured to the upper end of the screen. This lead seal is usually set between this blank joint of pipe 11 and the casing 4 as shown at 10.

In the lower end of the screen 6 is the usual spider 12, and secured thereto in the usual and customary manner is the back pressure valve 13 which is threaded into the collar 14 in the usual and well known manner.

Immediately above this spider 12 is the plug 15, and resting upon the upper end of this plug is the wash pipe 16 upon the upper end of which my improved valve 17 is 75 threaded.

This valve is substantially of an inverted cup like form and one end is provided with an annular shoulder 18, and a small port 19 is bored through this last mentioned end. 80 Immediately below this shoulder are a plurality of lateral holes 20 and 21.

The operation of the device is as follows: The ring 9 is placed between the ends of two joints of pipe and held in position by means 85 of the collar 8 and above the usual lead seal 10. The valve 17 is screwed onto the upper end of the wash pipe 16, which may be of any desired length. The wash pipe is inserted through the ring to the bottom of the screen and rests upon the annular plug 15. The passageway in the wash pipe and the hole, through the plug 15 are in alignment with the back pressure valve 13, hereinabove described. When the set pipe 5 is 90 backed out of connection at some joint, as at 22, and is raised up, the ring 7 will come in contact with the shoulder 18 of valve 17, and will block the openings 20 and 21 of the wash pipe and thus stop practically all 95 of the flow of fluid through the wash pipe which will cause an excessive pressure on the pump choking the pump down to a very slow stroke thus making it known that the set pipe is released from the seal 10 and that 100 the screen is consequently properly set.

The small opening 19 in the top of the valve 17 is for the purpose of permitting only sufficient fluid being pumped through same to wash the inside of the screen during the withdrawal of the wash pipe. It is 110 impossible to elevate the ring 7 to contact

with the shoulder 18, and close off the flow of fluid through the wash pipe, unless the set pipe is completely released from the pipe below, leaving the seal in proper place. 5 Therefore, it is evident to the driller where the desired result has been accomplished. If, after drawing up the set pipe 5 a short distance, the pumps do not slow down, it is then evident that the set pipe has not been 10 disconnected from the seal and another attempt must be made to disconnect it.

What I claim is:

1. The combination with a set pipe, of a seat within said pipe a wash pipe within the 15 set pipe, a cage like valve on the upper end of the wash pipe, said valve being provided with a port in the side thereof, and a restricted water passageway, extending lengthwise therethrough, and an external 20 projection on said valve adapted to rest on said seat.
2. In combination a wash pipe, a cage attached to the upper end thereof, an external lateral projection carried by the cage, 25 said cage having a port through the side thereof on one side of the projection, and a restricted port therethrough on the other side of the projection, and a ring through which the wash pipe extends and on which 30 said projection is adapted to seat.
3. In combination with a wash pipe having its upper end threaded, a cage screwed onto said threaded end of said wash pipe, a lateral port in said cage, an annular 35 shoulder carried by said cage and a ring upon which said shoulder is adapted to seat.

4. In a device of the character described, the combination with a set pipe of a seat between two sections of said pipe, a wash pipe within said set pipe, a cage-like valve 40 on the upper end of said wash pipe, said cage being provided with a port in the side thereof, and a restricted water passageway extending lengthwise therethrough, and a shoulder on the said cage adapted to seat on 45 said seat.

5. In combination, a wash pipe, a cup like valve attached to one end thereof, said valve having a lateral port and an external 50 annular shoulder.

6. In combination, a wash pipe, a valve carried by one end thereof, and formed with an annular external shoulder and a lateral port adjacent said shoulder.

7. In combination, a wash pipe, a valve 55 carried by one end thereof, said valve having an end port, an annular shoulder carried by said valve, said valve having a lateral port beneath the shoulder.

8. In a device of the character described, 60 a wash pipe, open at its lower end and whose upper end has an outward projection, and a lateral opening beneath said projection.

In testimony whereof I have signed my 65 name to this specification in the presence of two subscribing witnesses.

ALEXANDER THOMSON.
